UNITED STATES PATENT OFFICE.

ALFRED C. McCLOSKEY, OF PHILADELPHIA, PENNSYLVANIA, ASSIGNOR TO HIMSELF AND
CASPER S. BUTCHER, JR., OF PHILADELPHIA, PENNSYLVANIA.

JAR-CLOSURE.

No. 907,166.

Specification of Letters Patent.

Patented Dec. 22, 1908.

Application filed December 26, 1907. Serial No. 408,169.

To all whom it may concern:

Be it known that I, ALFRED C. McCLOSKEY, a citizen of the United States, residing at Philadelphia, county of Philadelphia, and 5 State of Pennsylvania, have invented a new and useful Improvement in Jar-Closures, of which the following is a full, clear, and exact description, reference being had to the accompanying drawings, which form a part of 10 this specification.

The object of my invention is to provide a closure for a jar adapted for the reception of preserves, condiments, canned goods and the like, which will absolutely exclude the 15 ingress of air so as to preserve the contents indefinitely, and which may be readily removed and replaced.

It is also my object to provide a closure having the foregoing characteristics which 20 will be simple in construction and inexpensive to manufacture.

These objects are attained in the closure illustrated in the accompanying drawings, in which —

25 Figure 1 is a perspective view of the jar sealed and covered and with fastener applied to the lid. Fig. 2 is a vertical sectional view of the same. Fig. 3 is a perspective view of the closing cap. Fig. 4 is a perspective view 30 of the gasket. Fig. 5 is a perspective view of the fastener for the lid.

The inner wall of the jar *a* is cut away circumferentially at its top to form an annular ledge or shoulder *b*. The jar is swelled outwardly near its top to form a projection *c* having a flat upper surface or ledge *d* whose width is increased by reducing the thickness of that part of the jar above the projection. 35

The cap comprises the base *e* from the periphery of which projects upwardly the rim *f*. From the upper edge of the rim projects outwardly the flange *g*, having an annular shoulder or ledge *j* near its periphery. The base *e* is of a slightly curved form so as to 45 form a concavity in its lower face. In the center of the base is a small orifice *h* preferably surrounded by a flange on the upper face so as to extend the length of the orifice and adapt it to receive a cork or stopper *i* 50 preferably of compressible material such as cork or rubber. *k* is a gasket of cork, rubber, or other compressible material adapted to surround the rim *f* and underlie the flange *g*.

55 The cap is applied in the following man-

ner. The jar is substantially filled with the preserves, which should be highly heated when introduced into the jar. The cap is then applied to the jar, the rim *f* and gasket *k* extending within the jar, and the cap is 60 pressed down into position. The part of the gasket *k* below the shoulder *b* is thus compressed between the jar and cap, while the upper part of the gasket is forced or bulged outwardly by the shoulder *j* so as to partly 65 overlie the shoulder *b*, thus forming a tight joint between the cap and jar. The application of the cap will displace the excess of preserves upwardly and cause it to exude from the orifice *h*. The stopper *i* is then inserted 70 into the orifice *h*. On cooling a partial vacuum will be formed in the upper part of the jar, and the pressure of the atmosphere will force the cap into place more and more tightly as the contents cool, thereby effecting 75 a perfectly air-tight closure.

The outer wall of the rim *f* should be beveled upwardly and outwardly. To remove the cap, all that is necessary is to insert the blade of a knife or other convenient edged 80 tool between the flange *g* and the upper edge of the jar. Owing to the bevel of the rim *f*, when once one edge of the cap is slightly raised, the joint is broken and the vacuum relieved, and very little additional force is 85 required to entirely remove the cap.

After the cap is applied as described, the flanged lid *l* is placed on the jar so that the lower edge of its flange rests above the ledge *d*. To hold the lid in position, there is provided the fastener shown in Figs. 1 and 5, which is composed of a single piece of wire. This wire is bent to form a central curved yoke *m*, from each end of which the wire is bent upwardly, as at *n*, thence horizontally 90 forwardly, as at *o*, and thence downwardly, as at *p*, the last named downward bends having their extreme ends bent somewhat backwardly. The wire is made of spring metal, and the horizontal bends converge from the 95 yoke toward their free ends. The edge of the lid *l* is cut away at *r*, Fig. 1, so that, when the jar is in use, the lid may be applied to the jar, while the bowl end of a spoon remains 100 therein, the shank or handle of the spoon 105 projecting through the recess *r* in the lid.

To apply the fastener, the free ends of the fastener are forcibly separated and the fastener applied to the jar, as shown in Fig. 1, so that the yoke *m* underlies the projection *c*, 110

- the bends *o* overlie the lid, the bends *n* and *p*, extend alongside the projection *c* and the flange of the lid *l*, while the extreme ends of the bends *p* extend under the projection *c*.
5 Owing to the elasticity of the wire and the tendency of the free ends of the fastener to spring together, the lid will be held on the jar by both a downward pressure and a lateral pressure. To remove the fastener, the free
10 ends thereof are merely sprung further apart and the fastener slipped off.

Having now fully described my invention, what I claim and desire to protect by Letters Patent is:

- 15 1. The combination with a jar whose wall is narrowed near its upper edge to form an internal annular ledge, of a cap comprising an orificed base having an upwardly extending rim inclined somewhat outwardly and an
20 annular shouldered flange extending outwardly from the rim and adapted to overlie the upper edge of the jar, a stopper adapted to close the orifice in the cap base, and a

compressible gasket adapted to surround the rim and be confined by the rim and flange 25 against the inner wall of the jar so as to partly overlie said ledge.

2. The combination with a jar whose outer wall is cut away to form an external annular ledge, of a compressible gasket adapted 30 to be confined against the inner wall of the jar, a cap comprising an orificed base and an upwardly and outwardly extending rim adapted to so confine said gasket, a stopper adapted to close the orifice in the cap, and a lid adapted to overlie the cap and having a depending annular flange extending outside the cap rim and adapted to overlie the said ledge. 35

In testimony of which invention, I have hereunto set my hand, at Philadelphia, on 40 this 23rd day of December, 1907.

ALFRED C. McCLOSKEY.
